UNITED STATES PATENT OFFICE.

THEODORE MAYER, OF NEW YORK, N. Y., ASSIGNOR TO MAX MAYER & SONS CO., INC.,
OF NEW YORK, N. Y., A CORPORATION OF NEW YORK.

DESIGN FOR A KNITTED JACKET.

Application filed January 5, 1924. Serial No. 8,249. Term of patent 3½ years.

To all whom it may concern:

Be it known that I, THEODORE MAYER, a citizen of the United States of America, and a resident of the borough of Manhattan, city, county, and State of New York, have invented a new, original, and ornamental Design for a Knitted Jacket, of which the following description, in connection with the accompanying drawing, is a specification.

Referring to the drawing, Figure 1 is a plan view of the front of the garment; and Figure 2 is a similar view of the rear of the garment.

I claim as my invention:

The ornamental design for a knitted jacket, as shown.

THEODORE MAYER.
